UNITED STATES PATENT OFFICE.

WILLIAM W. ROBBINS, OF LORAIN, OHIO.

MINING MACHINERY.

1,392,598.

Specification of Letters Patent.

Patented Oct. 4, 1921.

Application filed October 11, 1920. Serial No. 415,971.

To all whom it may concern:

Be it known that I, WILLIAM W. ROBBINS, a citizen of the United States, residing at Lorain, in the county of Lorain and State of Ohio, have invented certain new and useful Improvements in Mining Machinery; and I do hereby declare the following to be a full, clear, and exact description of the invention, such as will enable others skilled in the art to which it appertains to make and use the same.

My invention relates to improvements in mining machinery, and more particularly it relates to mining machinery of the power operated type.

Among the objects of my invention, are the following:—

To provide a power operated mining machine in which a hollow tool is thrust directly into the walls of the mine, with the result that the inner chamber of the tool is charged with the material being mined.

To provide a machine of the above character in which the tool is withdrawn by power.

To provide a machine of the above character, in which when the machine is withdrawn, the material being mined is automatically discharged from the chamber with the tool.

Another object of my invention is to provide certain details of improvement tending to increase the efficiency and serviceability of machines of the above character.

My invention, to accomplish the foregoing and other useful ends, consists of means hereinafter and more fully claimed.

Referring to the accompanying drawing, Figure 1 is an elevation of the machine. Fig. 2 is a side view of the same, partly in section. Fig. 3 is a section on line 3—3, Fig. 2.

In connection with my invention, I contemplate providing a track on the floor of the mine, the rails 2 of which I have shown. This track runs substantially parallel with the walls in the mine from which the material is to be removed. On these rails, I run a car, having a platform A. On this platform, there is provided a track at right angles to the track 2 on the rails 3, which are also shown. Under the car A I provide a suitable motor B for running the car A along the track 2. Arranged to run on the track, I provide a car C provided with wheels 4. Underneath the platform 5 of

this car, I provide a suitable motor D for moving the car C along the track on the platform A. On this platform, there are provided a pair of up-right members 6 and 7 which serve as bearings for a cylinder E. This cylinder is provided with flanges 8 and 9 for preventing the cylinder E from sliding through the bearings 6 and 7 in a longitudinal direction.

Along the cylinder E, I provide also a set of gear teeth 10, meshing with a suitable pinion 11 underneath the cylinder E. This pinion is mounted on a shaft 12 provided with suitable bearings in the members 6 and 13. The shaft 12 is arranged to be driven by a suitable motor 14, in order that the cylinder E may be rotated about its longitudinal axis. Within the cylinder E, I provide a plunger F, having grooved flanges 15, 16 adapted to receive corresponding key guides 17 on the inner walls of the cylinder E. The details of this arrangement are more clearly shown in Fig. 3.

The plunger F is secured at its inner head 17 to a piston rod 18. Within the plunger F, there is provided a disk 19 mounted on the rods 20, which latter are secured to the left hand head of the cylinder E. On the left hand end of the plunger 5 and in juxtaposition to the cylinder E, is provided a piston cylinder G, in which the piston 21 reciprocates. This cylinder G is mounted on the shelf 22, and suitably secured thereto. For the purpose of operating the piston, I provide a pipe 23, which pipe may lead to any suitable source of power, such as a water tank. This pipe branches off into two sections being provided with a valve 24 on one section and the valve 25 in the other section.

On the opposite side of the cylinder G, I provide an exhaust pipe 26, in which unite a pair of exhaust branches, one with an exhaust valve 27 and the other with an exhaust valve 28.

Projecting to the rear of the car C, I provide a frame work H serving as a shoe. The object of this shoe is to make it possible to brace the car C against the beam 29, which beam may be secured in position in any suitable manner, as for example through the medium of a jack-screw 30 between the floor and the ceiling of the mine.

With the means thus shown and described, it will be seen that I can place the car C in any desired, elected position where a mining operation is to be conducted, then by

- properly manipulating the valves 24, 25, 27 and 28, the piston 21 can be made to operate the plunger F so as to drive the plunger into the wall. When this takes place, of course 5 the material encompassed within the circumferential margin 31 of the plunger F is carved out of the wall and deposited in the plunger F upon the forward stroke of the piston 21. Upon the reverse operation, the 10 material thus captured, is withdrawn from the wall and as it is withdrawn, the disk 19 automatically dumps the material thus withdrawn on the floor below, between the track 2 and the wall.
- 15 Under conditions where the material is not disengaged readily by the mere forward stroke of the plunger F, the process of disengagement is insured by the bringing 20 into play the motor 14. By operating this motor, the pinion 11 is operated thereby rotating the cylinder E, and consequently rotating the plunger F.

With reference to the forward edge 31, of the plunger F, this cutting edge may be, of course, maintained sharpened as indicated in the drawing, to facilitate the digging operation. This edge may be sharpened from time to time, as is needed. Of course in time the plunger F will become shortened, in 30 which case, the plunger F may be replaced by a new one.

It will be understood also that if desired, I may provide a conveyer of any suitable type such as of the endless belt type between 35 the track 2 and the wall on the right, not shown, on to which the material from within the plunger F, may be caused to fall and automatically carried out.

What I claim as my invention is:

- 40 1. In a mining machine, the combination of a piston, a cylinder therefor and hydraulic means for operating said piston, a cylindrical mining tool on the end of said piston, and operated thereby back and forth, a 45 cylinder within which said boring tool is adapted to reciprocate in a telescopic manner, bearings for said cylinder, a spline connection between the tool and the cylinder,

whereby any rotary motion of the cylinder is communicated to the tool; a motor for rotating said cylinder whereby said tool may also be rotated. 50

2. In a mining machine, the combination of a piston, a cylinder therefor and hydraulic means for operating said piston, a cylindrical mining tool on the end of said piston, and operated thereby back and forth, a cylinder within which said boring tool is adapted to reciprocate in a telescopic manner, bearings for said cylinder, a spline connection between the tool and the cylinder, whereby any rotary motion of the cylinder is communicated to the tool; a motor for rotating said cylinder whereby said tool may also be rotated, and a stationary disk 60 relative to said cylinder held within said tool, whereby the material captured by the tool may be automatically dumped out of the tool upon the return stroke of the tool. 65

3. In a mining machine, the combination of a piston, a cylinder therefor and hydraulic means for operating said piston, a cylindrical mining tool on the end of said piston, and operated thereby back and forth, a cylinder within which said boring tool is 70 adapted to reciprocate in a telescopic manner, bearings for said cylinder, a spline connection between the tool and the cylinder, whereby any rotary motion of the cylinder is communicated to the tool; a motor for rotating said cylinder whereby said tool may also be rotated, and a stationary disk 75 relative to said cylinder held within said tool, whereby the material captured by the tool may be automatically dumped out of the 80 tool upon the return stroke of the tool, a support for said disk, secured to the head of said second cylinder, said tool adapted to reciprocate along the said support, said support passing through the head of the tool to 85 which the piston rod is connected. 90

In witness whereof, I have hereunto signed my name this 25th day of September, 1920.

WILLIAM W. ROBBINS.
